COMBINATION FOOD AND BEVERAGE
BLENDER

Francesco Collura, New York, N. Y., assignor to
The Winsted Hardware Manufacturing Company, Winsted, Conn., a corporation of Connecticut

Application January 4, 1952, Serial No. 17,943

Term of patent 14 years

(Cl. D44—1)

To all whom it may concern:

Be it known that I, Francesco Collura, a citizen of the United States of America and a resident of the city of New York, State of New York, have invented a new, original, and ornamental Design for a Combination Food and Beverage Blender, of which the following is a specification, reference being had to the accompanying drawing, forming part thereof, wherein:

Fig. 1 is a side elevational view of a combination food and beverage blender showing my new design; and

Fig. 2 is a top plan view thereof with the container shown in broken lines in Fig. 1 omitted for convenience of illustration.

The essential features of my design reside in the portions shown in full lines.

I claim:

The ornamental design for a combination food and beverage blender, as shown and described.

FRANCESCO COLLURA.
